(57) **CLAIM**

The ornamental design for a case for control device, as shown and described.

DESCRIPTION

FIG. 1 is a perspective view of a case for control device design showing my new design.

FIG. 2 is a front view of the case for control device of FIG. 1.

FIG. 3 is a rear view of the case for control device of FIG. 1.

FIG. 4 is a left side view of the case for control device of FIG. 1.

FIG. 5 is a right side view of the case for control device of FIG. 1.

FIG. 6 is a top view of the case for control device of FIG. 1.

FIG. 7 is a bottom view of the case for control device of FIG. 1.

FIG. 8 is an enlarged view of the portion of the case for control device encircled in FIG. 2; and,

FIG. 9 is an enlarged view of the portion of the case for control device encircled in FIG. 7.

Any shading and cross-hatching are not features of the design but are utilized to illustrate the surface contours of the case for control device design in the drawings.

The broken lines shown in FIGS. 2, 7, 8, and 9, which form no part of the claimed design, encircled portions of the case for control device that are illustrated in enlargement. The broken lines shown in FIG. 3 illustrate portions of the case for control device which form no part of the claimed design.
